COMBINED BINDER AND DISPLAY EASEL

Elmer W. Ericson, Chicago, Ill.

Application October 6, 1950, Serial No. 188,720

2 Claims. (Cl. 281—33)

1

This invention relates to improvements in a combined sheet-like body binder and display easel, having for an object to provide a cheap, durable, strong and simply operable product in which sheet-like bodies, such as advertising displays, mats, photographs, and various other similar devices can be arranged in juxtaposed relation and connected or mounted therein for swinging movement, plus convenient, easy and quick mounting for such swinging movement and/or removal therefrom.

It is also an object of the invention to provide a combined binder and display easel which, by simple and easy adjustment, or readjustment, can be instantly converted from a binder into a secure and sturdy easel display whereon a plurality of sheet-like bodies will be swingably supported and capable of selective individual or collective turning from non-display to display positions, or vice versa.

Another object of the invention is to provide a combined binder and display easel of the indicated character, wherein the sheet-like body mounting means, and particularly, the binder backbone is capable of a limited pivoting movement as and when the sheet-like bodies connected to and mounted on the same are swung from one position to another, i. e., from a non-display position to a display position, or vice versa, allowing such bodies, as the aggregate weight thereof accumulates on one side or the other of the easel, to hang from the mounting flatly against and over the area of the particular side of the easel adjacent which the same are arranged and thereby materially improve their positions of display, as well as ensure the positive though movable retention of the bodies of their swung or turned positions.

The foregoing, as well as other objects, advantages and meritorious teachings of my invention, will be in part obvious and in part pointed out in the following detailed disclosure thereof, when taken in conjunction with the accompanying drawings, it being understood that the forms of the invention presented herein are precise and what is now considered to be the better modes of embodying its principles, but that other modifications and changes may be made in specific embodiment without departing from its essential features.

In the drawings:

Figure 1 is an end elevation of the invention showing the same in closed or book-like form.

Figure 2 is a perspective showing the device of the invention in easel form and sheet displaying position.

2

Figure 3 is an enlarged transverse, vertical section through the back and portions of the cover panels in easel form and displaying position, illustrating the motion arrested position of the back with relation to the cover panels as the result of the pendent aggregate weight of successively displayed sheets adjacent one of said panels whereby said sheets hang flatly adjacent the same.

Figure 4 is a view similar to Figure 3, showing a modified form of spine member for the device back, and,

Figure 5 is a detail in perspective of the form of spine member shown in Figure 4.

Referring in detail to the accompanying drawings, particularly, to that form of the invention illustrated by Figures 1-3 thereof, the same includes, preferably, though not necessarily, complementary stiff cover panels 1 and 2 and a back

3. The cover panels can be covered or sheathed in suitable material 4, portions of which are extended from one side of one of the panels to the corresponding side of the other. Thereby, the spanning back 3 is provided with its opposite sides hingedly or swingably connected to the aforesaid sides of the panels 1 and 2.

A substantially stiff panel-like extension 5, of suitable width, is hinged or swingably connected as at 6, to the remaining side of the panel 2 and carries a flap 7 on its free end adapted, with easel-like positioning of the cover panels 1 and 2, to overlie a lower portion of the panel 1 and to be detachably connected thereto by appropriate fasteners or separable fasteners 8 (see Figure 2).

Other separable fastener members 8' may be and preferably are mounted on the inner face of the extension 5, in proximity to its hinging to the panel 2, and with arrangement of the binder in closed position (see Figure 1), are adapted to be engaged with the component fastener members 8 on the cover panel 1. Thus, the binder will be locked in its closed position.

The back 3, in addition to the spanning portion of the material 4 between the cover panels 1 and 2, consists of flat rectangular stiff strips 9, 9' and 9^a of corresponding lengths and successively decreased widths, as shown in Figure 3. Said strips are juxtaposed in the relation shown, joined by a positive adhesive or other suitable means, and longitudinally inserted into and between the plies of material 4 of the back 3. Thereupon, the ends of the back forming material are preferably closed over the opposite ends of the flat stiff strips so as to completely encase the same.

Because of the successively decreased widths of the flat stiff strips 9, 9' and 9^a and their joined

relation, it will be seen that the opposite sides of the back assembly 3 will be stepped or substantially bevelled in opposite directions; also that the inner and outer faces thereof will be flat throughout their respective areas, the purpose of which will be hereinafter understood.

A binding assembly, including a base or body 11, mounting spaced suitable loose leaf binder rings 12 thereon, is fixedly engaged longitudinally of and along the normally inner and wider side of the back assembly 3 substantially throughout its length. Spaced rivets 13 are passed through and connected to adjacent portions of the base 11 and the adjacent wider stiff strip 9, thereby effecting the aforesaid fixed engagement.

Sheets 14, of appropriate shape and/or size, are adapted to be detachably and loosely engaged with the binding assembly rings 12, being swingable over and about the same in a manner similar to book page turning.

When the device is used as a display easel, the separable fasteners 8 and 8' are disengaged. Thereupon the cover panels 1 and 2 are swung from the position shown in Figure 1 so as to substantially reverse their relating, bringing them into the inverted V-shaped formation shown in Figure 2. The extension 5 is now moved to span the spaced lower sides of the panels 1 and 2 and its flap 7 is overlappingly engaged with the lower side of the panel 1 and detachably connected thereto by interengaging the fastener members 8.

The sheets 14 engaged with and depending from the binder rings 12 may all be arranged adjacent the panel 1 (see Figure 2). When in such a position, the aggregate weight of such sheets will be sufficient to cause downward swinging of the near side of the back 3, the binder ring base 11 and rings 12, and upward and outward swinging of the opposite side of said back. The swinging movement of the back assembly will be arrested or limited by the abutting engagement of the above described bevelled or angled upper and outer side of the back 3 with an adjacent portion of the panel 2 and so, solid support will be accorded said back assembly and the pendent sheets. Moreover, said pendent sheets will be substantially flat against and over the adjacent face of the panel 1, thereby materially improving their display.

Assuming now that the sheets 14 supported adjacent the panel 1 are to be hinged or turned on the binder rings 12 for successive display adjacent or over the panel 2, it will be seen and appreciated that as they are to be turned, the increasing weight thereof pendant from said rings will cause the back assembly to swing so that its side hinged to the panel 2 will move downwardly, while its opposite side, hinged to the panel 1, will move upwardly and outwardly. As the number and hence, the weight of these turned sheets increases, the now lower bevelled or angled side of the back will abut an adjacent portion of the panel 2. Consequently, the swinging movement of the back assembly in this particular direction will be arrested and/or limited and solid support will be provided to the same and the sheets hanging therefrom over the panel 2. By the same token, these sheets will be arranged substantially flat against and over the adjacent face of said panel 2 for now manifest reasons.

A user, having no further or immediate need for the display easel, as above, and desiring to return the device to its closed or book-like form (see Figure 1), disengages the separable fasteners 8; swings the extension 5 and flap 7 from its spanning position to one adjacent the now outer

face of the panel 2; swings the panels 1 and 2 upwardly until they are brought in substantially parallelism, as shown in Figure 1, and then interengages the fasteners 8 and 8' as also shown in said figure.

At this point attention is called to the fact that the narrower side of the back 3 is outermost when the combined binder and easel is in its closed position; also and quite important, that because of the flat, continuous surface provided thereby, suitable intelligence can be advantageously and effectively presented thereon and thereby in a durable, economical manner.

In Figures 4 and 5 of the drawings, I have shown a slightly modified form of spine member for the back assembly of the invention. Instead of making the spine member of laminated construction, i. e., the juxtaposed and joined stiff strips 9, 9' and 9^a, the spine member may be made of a single or one piece construction, indicated at 15. It may be formed of metal, plastic, wood or other suitable materials and/or combinations thereof, such as conditions or preference may dictate, having flat and relatively substantially parallel inner and outer faces and opposite sides bevelled or angled in opposite directions, as shown at 16.

This spine member 15 is snugly received between the plies of the material 4' of the back 3', whose open ends may be and preferably are closed thereover, as shown in Figure 1 of the drawings. Thereby, the back assembly is provided with angled or bevelled sides which serve the same purpose as the like sides of the laminated spine members 9, 9' and 9^a.

To fixedly mount the loose leaf binder ring carrying base or body 11' on the above back assembly, spaced rivets 13' are passed through the same and adjacent portions of the spine member 15 and are appropriately anchored. Preferably, said rivets are not engaged through the adjacent or outer ply of material 4' of the back 3'. Thus, a continuous and unbroken surface is provided thereto on which intelligence can be economically and effectively printed or otherwise presented.

The angle or bevel of the opposite sides of the laminated spine member 9, 9' and 9^a and/or the one piece spine member 15, it is to be understood, may be at various and different degrees, though it is not considered necessary that the same shall be less than 90° or a right-angle, in order that the back assemblies or either of them shall be permitted an extent of movement such as exemplified by the accompanying drawings.

The purpose of or reason for angling or beveling the opposite sides of the laminated spine members 9, 9', 9^a and the one piece spine member 15, it will be understood is to permit the reverse positioning of the cover panels to 1 and 2 and their more or less flushly abutting engagement with the opposite sides of said spine members in the manner shown in Figures 2, 3 and 4 of the accompanying drawings. Suitable abutting engagement, under similar conditions or positions of the panels 1 and 2 may be assured where the spine member is of laminated or one piece construction with an overall rectangular formation, i. e., the opposite longitudinal sides of such member being at right angles to the inner and outer faces of the same.

Further describing my invention, it is of essence that (1) the hinging or pivoting of the cover panels 1 and 2 shall be effected, via the back sheathing 4, adjacent to or even directly to the normally inner edges or extremities of the

opposite longitudinal sides of the spine members 9, 9', 9^a or 15, and, (2) that, preferably though not absolutely necessarily, the depths or thicknesses of said spine members shall be substantially greater than said cover panels 1 and 2. Thus, when these cover panels are hingedly position reversed in the manner well shown in Figure 2, portions of their now inner sides will be selectively and individually abuttingly engageable with and over the opposite longitudinal sides of the spine members 9, 9', 9^a or 15, or the now inner and free edges of said longitudinal sides. In consequence, an efficient motion limiting or stop means will be provided to the spine members or back assembly for those purposes and reasons hereintofore fully described.

Because of the hereinbefore described adjustability of the book back and/or the spine, the invention when set-up as an easel, will operate to flatly hang displayed sheets from the binding mechanism over either of the adjacent faces of the panels 1 or 6, i. e., they will be prevented from flexing adjacent and along those portions of the same which are engaged on the retaining rings 13 when turned to displaying positions. In consequence, the need for use of fabric hinge strips or stubs and joining the same to inner end portions of sheets whereby to space said sheets from the rings 13 for distances sufficient to ensure their flat pendant positioning adjacent the panels 1 or 6 will be eliminated. Thereby, a material saving in production costs is effected.

I claim:

1. A combined binder and easel, comprising stiff relatively opposed and spaced cover panels, sheet-like material disposed over and covering said panels and spanning the space therebetween forming a spine receiving and retaining flexible means, a stiff spine member snugly in and longitudinally of said receiving and retaining means being of a width less than that of the sheet-like material spanning the space between the stiff cover panels and spaced from said panels, the opposite sides of the spine member being beveled, relatively converging and individually abuttingly engageable with adjacent portions of said panels, at times, the opposite faces of the spine member being flat throughout their entire areas, binder means disposed longitudinally of the normally inner and wider face of the spine member over the adjacent spanning portion of said sheet-like

material, means connecting the binder means to said spine member through said adjacent spanning portion of the sheet-like material, said connecting means being covered by the remaining spanning portion of said sheet-like material, and an extension hinged to the free side of one of the panels detachably connectible to the free side of the remaining panel whereby to, at times, retain the same in spaced relation.

- 5 5. 2. A combined binder and easel, comprising stiff relatively opposed and spaced cover panels, sheet-like material disposed over and covering said panels and spanning the space therebetween, forming a spine receiving and retaining flexible means, a stiff spine member snugly in and longitudinally of said receiving and retaining means being of a width less than that of the sheet-like material spanning the space between the stiff cover panels and spaced from said panels, said spine member consisting of a plurality of juxtaposed interconnected coincidentally extending stiff flat strips of successively decreasing widths positioned with their opposite side portions in stepped relation whereby to provide relatively oblique and convergent opposite sides to said spine member, binder means disposed longitudinally of the normally inner and wider face of the spine member over the adjacent spanning portion of said sheet-like material, connecting means engaged through the normally innermost of the strips of said spine member and through the adjacent spanning portion of the sheet-like material fixedly engaged with said binder means, and an extension hinged to the free side of one of the panels detachably connectible to the free side of the remaining panel whereby to, at times, retain the same in spaced relation.
- 10 10. 3. 3. 4. 4. 5. 5. 6. 6. 7. 7. 8. 8. 9. 9. 10. 10. 11. 11. 12. 12. 13. 13. 14. 14. 15. 15. 16. 16. 17. 17. 18. 18. 19. 19. 20. 20. 21. 21. 22. 22. 23. 23. 24. 24. 25. 25. 26. 26. 27. 27. 28.
